Primary Examiner — Janice Seeger(74) **Attorney, Agent, or Firm:** Saidman DesignLaw Group, LLC(57) **CLAIM**

The ornamental design for a table, as shown and described.

DESCRIPTION

FIG. 1 is a perspective view of a table showing my new design; and,

FIG. 2 is an enlarged view of portion 2 encircled in FIG. 1. The dashed broken lines illustrate unclaimed environmental structure and the dot-dashed broken lines illustrate portions of enlargement; the broken lines themselves form no part of the claimed design.
